UNITED STATES PATENT OFFICE

JOSEPH BERGE, OF MONTCLAIR, NEW JERSEY, ASSIGNOR TO A C SPARK PLUG COMPANY, OF FLINT, MICHIGAN, A COMPANY OF MICHIGAN

SPEEDOMETER DRIVE MECHANISM

Original application filed May 16, 1921, Serial No. 470,062. Patent No. 1,670,836, dated May 22, 1928.
Divided and this application filed March 1, 1928. Serial No. 258,272.

The present invention relates to drive mechanism for speedometers such as are ordinarily used on motor vehicles. In such apparatus, the indicating member is usually arranged to turn on a vertical or substantially vertical axis, whereas it is generally essential that the driving shaft enter the speedometer casing at an angle to the vertical and it is common practice to employ a set of bevel or other gears as the connection between the driving shaft and the rotating member from which the indicating member derives its torque.

Due to inaccuracies in cutting or adjustment, or to wear consequent upon difficulties of lubrication, the gears tend to become noisy which is a serious objection, particularly in high grade cars. In accordance with one phase of the present invention, the gears are superseded by a flexible coupling, preferably a coupling of special construction which not only runs quietly at all times, but is also inexpensive to manufacture, easily installed and capable of giving uniform service throughout the life of the instrument.

The invention is further concerned with various other relations of parts and with various details of construction hereinafter pointed out.

30 In the drawings:

Figure 1 is a central vertical section showing a speedometer mechanism in which is embodied the present invention; and

Figure 2 is a perspective view showing the 35 detailed construction of the flexible coupling.

Referring to the drawings, 1 indicates the main element of the frame, preferably of aluminum, which conforms generally to the inner surface of the back 2 of a substantially cup-shaped casing 3, said frame including a forwardly extending cross wall 4 forming a bearing 5 having a vertical axis and also including a downwardly and rearwardly inclined extension 6 forming a bearing 7 for 40 a main hollow drive shaft 8. Connection for driving the latter from a flexible shaft 9 is made preferably by means of a non-circular end portion 10 and socket 11 with which the shafts 8 and 9 are respectively provided.

45 The casing for the flexible shaft appears at

12 and is preferably connected with the extension 6 in the manner set forth in my United States Patent No. 1,324,787, December 16, 1919. It will be understood that the driving connection 9, 10 permits relative longitudinal movement of the parts. At its inner end the shaft 8 is enlarged and forms a worm 15 positioned in driving engagement with the worm wheel 16. Suitable gearing is provided between the worm wheel 16 and the 55 shaft 17 whereby the odometer mechanism 18, 19 is driven. A collar 20 pressed on the lower end of the shaft 8 serves to retain the latter in its bearing.

50 Mounted in the bearing 5 is an upright hollow rotor shaft 21, preferably of soft iron or steel, on the upper end of which is secured preferably by press fitting a rotor 22. Above the rotor and extending downwardly around the same is mounted the speed cup 23 supported in any suitable manner, as upon the spindle 24. It will be understood that the speed cup is adapted by connection to any suitable indicating device or by the provision of indicia upon its periphery for giving indications of the extent of deflection of the speed cup caused by the magnetic influences set up by rotation of the rotor. The magnetic field necessary for instruments of this type is produced by a horseshoe magnet 25.

55 For driving the rotor shaft 21 from the main shaft 8, a flexible coupling 26 is provided, the same being preferably formed of a steel wire core 27 surrounded by four layers each of four small similar wires 28 alternately wound in opposite directions, such cable being in common use in dental machines and the like. It is desirable that the connection between the cable and the shafts 8 and 21 be of a type such as permits longitudinal movement of the cable axially of the shafts, thereby allowing the cable, by reason of its resiliency, to assume a truly circular arc and avoiding excess local stresses. Such connections may be conveniently formed by soldering the wires of the cable together at the ends and fitting them into metal tips 29 substantially square in cross section and thereafter indenting the walls of the tips into the formed ends of the cable by means of a 60

suitable tool, as indicated at 30. The inner surfaces of the shafts 8 and 21 are, of course, shaped by broaching or otherwise as shown at 31 to receive and conform to the tips 29, a slight clearance being, preferably provided. In assembling, the cable is first inserted into the shaft 8, the upper end of the cable is next inserted into the bearing 5. The shaft 21 is then inserted from above into said bearing 10 (in which process it receives the tip 29) and a collar or sleeve 32, which was initially threaded over the cable, is finally pressed upwardly on to the lower end of the shaft 21 to retain the latter in position.

15 It will be noted, as suggested heretofore, that the cable 26 is free to assume its natural position, there being no flexible casing such as is in universal use in flexible shafting of this nature. So far as I am informed, I am 20 the first to employ a floating cable, such as the cable 26, as a means for transmitting driving torque between two shafts regardless of the particular instrument or association of which it forms a part, and regardless of 25 whether the axes are inclined to each other, offset from each other or parallel.

As a means for lubricating the worm gearing 15, 16 as well as the shaft 8, a pad 33 of saturated felt or the like encircling the shaft 30 8 between the worm 15 and the casing and disposed between the casing and the gear 16 may be employed. For additional lubrication of the shaft 8, it may be advisable to employ a packing 34 of similar material inserted in a 35 hole in the frame. A felt washer 35 or the like is used to seal the joint between the frame and the casing.

This application is a division of my application, Serial No. 470,062 filed May 16, 1921, 40 now Patent Number 1,670,836, May 22, 1928.

I claim:

1. In combination, two members rotatable in fixed positions about axes at an angle to each other, and a built-up flexible wire cable 45 connecting said members to drive the one from the other, said cable being free to move axially thereof between said members and to accommodate itself to the form naturally imposed thereon by the transmission of 50 driving torque.

2. In combination, a member rotatable about a substantially vertical axis, a main driving shaft having an axis at an angle thereto, and a resilient flexible longitudinally floating coupling connecting the driving shaft to the rotatable element, said coupling being supported solely by said driving shaft and said rotatable element and its extent of longitudinal floating movement being 55 such as to permit it to assume substantially the arc of a circle throughout its length.

3. A magnetic speedometer comprising a rotor and rotor shaft rotatable about a substantially vertical axis, an inclined driving shaft, and a built-up flexible wire cable sup-

ported solely by said shafts at all times and freely movable longitudinally in respect thereto into the regular curve naturally imposed thereon by the transmission of torque for driving the rotor from the main driving shaft.

4. In combination, two rotatable members inclined to each other and having sockets of polygonal cross-section, a flexible wire cable comprising a plurality of reversely wound 75 layers of wire and having end portions conforming to and longitudinally slideable in the corresponding one of said sockets, said sockets constituting the sole support for said cable at all times.

5. In combination, two rotatable members inclined to each other and having sockets of polygonal cross-section, a flexible wire cable comprising a plurality of reversely wound 85 layers of wire and having end portions separate from said wire layers and crimped thereon, said end portions conforming to the sockets and being slideable longitudinally therein and serving as the sole support for the wires of said cable at all times during 90 the normal operation thereof.

6. In combination, two rotatable members inclined to each other and having sockets each forming bearing surfaces at right angles to planes of rotation of said member, a flexible wire cable comprising a plurality of reversely wound layers of wire and having hollow end portions forming bearing surfaces corresponding to said first-named bearing surfaces and slideable longitudinally 95 therewith to an extent such as to permit said cable to assume a substantially regular curve imposed upon it by the torque transmitted, said hollow end portions being pressed down onto the cable, said cable being supported 100 solely by said bearing surfaces under all conditions of normal operation.

7. In combination with the rotor structure of a speedometer and the main driving shaft thereof, a common frame wherein said shafts are rotatably supported at an angle to each other materially greater than a right angle, said shafts being provided internally with shaft holding sockets, and a flexible built-up wire shaft having end portions received in 110 said sockets and non-rotatable in respect thereto and free to move lengthwise of said sockets during the normal operation of the speedometer and being supported solely 115 thereby under all conditions of normal operation.

8. In a speedometer, a casing, a frame having a bearing, a rotor carried in said bearing and rotatable about a substantially vertical axis, a drive shaft also carried by said frame and rotatable about an axis inclined to the vertical, said drive shaft and said rotor each having axial sockets in the ends thereof proximate each other, and a flexible shaft connecting 125 said drive shaft and said rotor, said flex- 130

ible shaft being assembled by insertion into the socket in the drive shaft and into said bearing and by thereafter shifting the rotor longitudinally in said bearing to receive the 5 flexible shaft in the socket in said rotor, said coupling being supported under all conditions of normal operation solely by said members.

9. The combination with a driving shaft 10 and a driven shaft which are not in axial alignment of a laterally flexible coupling member having one end in axially slidable engagement with said driving shaft and the other end in axially slidable engagement with 15 the driven shaft, said ends being formed to transmit rotative motion between said member and said shafts, said member being laterally unsupported intermediate said shafts and being free to assume a curved position 20 under the influence of the driving stresses and its lateral flexibility.

10. The combination with driving and driven shafts which are not in axial alignment of a laterally flexible and resilient wire 25 cable providing a driving connection between said shafts, said cable having driving elements at its ends and said shafts having co-operating driving elements, said elements constituting rotative driving and axially 30 slidable connections between said cable and said shafts at each end of said cable, the intermediate portion of said cable being laterally unrestrained and free to assume a curved position as determined by its resilience and 35 the driving torque.

11. The combination with two shafts whose axes are inclined to each other, of a driving connection between said shafts comprising a laterally flexible resilient wire cable 40 having its ends in rotative driving engagement respectively with said shafts, the intermediate portion of said cable being laterally unsupported and unrestrained and maintaining, by reason of its resilience, a curved position approximately in a circular arc.

In testimony whereof I affix my signature.
JOSEPH BERGE.
